B. K. Dinsont Thompson ATTORNEYS

UNITED STATES PATENT OFFICE.

ARTHUR HOLMES, OF CANTON, OHIO.

MANIFOLD.

1,375,909.

Specification of Letters Patent. Patented Apr. 26, 1921.

Application filed December 19, 1917. Serial No. 207,868.

To all whom it may concern:

Be it known that I, ARTHUR HOLMES, a citizen of the United States of America, and resident of Canton, in the county of Stark, in the State of Ohio, have invented new and useful Improvements in Manifolds, of which the following, taken in connection with the accompanying drawings, is a full, clear, and exact description.

0 This invention relates to certain improvements in internal combustion engines, and pertains more particularly to the inlet manifold or multi-cylinder engines of the type named.

5 With the ever decreasing volatility of the gasoline now being supplied for use in internal combustion engines, and particularly in cold weather until the motor warms up, it has been a more and more difficult problem to prevent one or more cylinders from getting more fuel in proportion to air as compared to other cylinders of the same engine using the same carburetor. This trouble is caused by the fact that the mixture traveling through the inlet manifold is not a homogenous gas, but a mechanical mixture of particles of unvaporized fuel, vaporized fuel, and air.

It is easy to distribute the air and truly vaporized fuel but the particles of unvaporized fuel, having a greater specific gravity than the former, present a different problem due to the tendency to throw such particles to one side at any bend in the passage and particularly under such condition as the turning of a corner in the inlet manifold, where inertia becomes effective, the unvaporized gas or liquid going in a straight line while the air and gas turn the corner without difficulty.

This fault in previous inlet manifolds makes it impossible to adjust the mixture at its origin in the carburetor so as to give the proper mixture in all cylinders, resulting in non-uniform operation and loss of power over what the engine would give with proper distribution of fuel, and in a tendency to soot the spark plugs and form carbon on the walls of the cylinders getting the rich mixture resulting in misfiring and other effects detrimental to the running qualities of the engine.

Designers have, in the past, made many attempts to correct this fault in the distribution of the mixture. One way has been

to apply heat to the mixture at the carburetor and during its passage to the various cylinders in an attempt to thoroughly vaporize the fuel and prevent condensation on its way to the cylinder. The difficulty with this method is that the amount of heat necessary to produce the required results is so great that it reduces the volumetric efficiency of the engine and often results in cracking, or disintegrating the fuel. Other attempts have been made along the line of making the path of the gases to the various cylinders equal in length, but designers of this type of manifold failed to take into consideration the fact that at the bends in the passages fuel is thrown out by centrifugal force and due to the shape of the manifold is thrown into one or more cylinders out of proportion to the remaining cylinders.

75 This invention takes into consideration the inertia of the free fuel and takes advantage of this inertia to obtain equal qualitative distribution of the mixture with the result that the engine is exceedingly smooth in operation at all times, the spark plugs are not fouled, and misfiring and other detrimental results are avoided.

80 Other objects and advantages of the invention relate to the details of construction and operation as will more fully appear from the following description, taken in connection with the accompanying drawings, in which—

85 Fig. 1 is a side elevation of a manifold made in accordance with this invention.

Fig. 2 is a horizontal sectional view of the same, illustrating a portion of the walls of cylinders of an internal combustion engine.

90 The drawings illustrate a manifold particularly designed for a six-cylinder engine, but it will be readily understood that this invention can be applied to a multi-cylinder engine of any number of cylinders, the structure shown being merely illustrative of one embodiment thereof.

95 As shown, the manifold embodies a main conduit —1— having at substantially its central point a depending branch —2— adapted to be connected in any suitable manner to a carburetor —3—. The main conduit —1— is provided with a series of branches —4—, —5—, —6—, —7—, —8— and —9—, as here illustrated six in number, 100 110

separate sets of three being arranged upon opposite sides of the carbureter branch —2—. Each of these branches communicates through a suitable passageway or inlet 5 with a cylinder of an internal combustion engine. These inlets are numbered, respectively, —10—, —11—, —12—, —13—, —14— and —15— and extend through the walls of 10 respective cylinders, such walls, in this illustration, being indicated as cast *en bloc*. It will be understood, however, that the construction of the cylinders, their form and arrangement is not material to the invention, although the manifold here illustrated 15 is particularly designed for use with a six-cylinder air cooled engine in which the cylinders are formed separately and spaced some distance from each other.

The branches —4—, —5— and —6— are 20 in all respects similar to the branches —9—, —8— and —7—, respectively, and preferably the branches are spaced equal distances apart. The branches —6— and —7— have their inner walls formed by a continuously 25 curved wall —16— substantially in the form of an arch and having its peak adjacent the edge of the carbureter branch —2—.

The outer walls —17— and —18— of the 30 branches —6— and —7— are curved inwardly in substantial conformity with the curvature of the wall —16— and terminate in points —19— and —20— adapted to act as deflecting surfaces.

The inner walls —21— and —22— of the 35 branches —5— and —8— likewise curve inwardly toward the carbureter branch —2— and symmetrically join the walls —23— and —24— of the conduit —1— along arcuate lines. The outer walls —25— and —26— of 40 these branches are curved substantially in conformity with the inner walls and extend beyond the walls —23— and —24— to substantially the central point of the conduit —1—, forming deflecting points or surfaces —27— and —28— lying midway of the conduit —1— for a purpose hereinafter described.

The outer walls —29— and —30— of the 45 conduit —1— are deflected outwardly adjacent the points —27— and —28— a distance substantially equal to the projection of the points —27— and —28— into the conduit —1—, so that the diameter of the conduit —1— is not diminished beyond the deflecting points —27— and —28—.

The branches —4— and —9— are 50 symmetrically curved inwardly to unite with the conduit —1— beyond the deflecting points —27— and —28— along arcuate lines. All of the branches preferably terminate in plane surfaces lying substantially parallel 55 with the axis of the conduit —1—.

The operation is substantially as follows: 60 When cylinder A draws its charge, a por-

tion of the fuel in passing point —27— will be thrown by its inertia into branch —5—, due to the position of the deflecting surface —27—, the air and vapor all going to branch —4—. The fuel thus deposited in branch —5— will remain there until cylinder B draws its charge. When this takes place, a portion of the free fuel will be thrown by its 70 inertia into the branch —4—, likewise due to the projection of the deflecting surface —27—, all of the air and vapor going to the branch —5— and its respective cylinder B. 75

As the division point or deflecting surface —27— is on the center of the conduit —1— feeding these two cylinders, the amount of free fuel thrown into branch —4— when branch —5— draws its charge, and into branch —5— when branch —4— draws its charge, should be substantially equal and is 80 in practice substantially equal, thus effecting an equal qualitative distribution to these cylinders. If there is any error or non-uniformity of distribution due to the influence of other cylinders, detected by observation or analysis, this can be corrected by shifting the deflecting surface —27— toward the branch which gets the richest mixture. The 85 operation is the same in connection with branches —9— and —8— as in connection with branches —4— and —5—. 90

The points —19— and —20— which divide the mixture going into branches —6— and —7—, respectively, present a somewhat different problem due to the fact that two cylinders draw from the conduit —1— beyond the connection of these branches, and the exact positioning of the points —19— and —20— will have to be determined on each design by experiment, but for the particular use for which the manifold here disclosed has been designed the form and arrangement shown upon the drawings has 100 proved correct in detail, and in this form and arrangement the points —19— and —20— lie substantially in alinement with the apex of the curved wall —16— and, due to the curvature of such wall as well as the curvature of the walls —17— and —18—, 105 act to deflect the requisite portions of the free fuel for passage to the other branches 110 of the manifold.

The manifold here shown and described 115 results in a substantially equal qualitative distribution of the mixture to each cylinder and prevents fouling of the spark plugs, carbonizing the cylinders, misfiring of the engine, and other undesirable effects, and 120 effects a more economical operation with the production of greater engine power, and although I have shown and described one 125 specific construction, form and arrangement as perhaps preferable and peculiarly applicable to a six-cylinder engine, it will be readily understood that the form, arrangement and construction of the manifold 130

may be varied and that the same may be applied to use with any multi-cylinder engine, without departing from the spirit of this invention as set forth in the appended claims.

5. What I claim is:

1. An inlet manifold for multi-cylinder engines comprising a main conduit having off-set portions and branch conduits communicating with the main conduit adjacent 10 the off-set portions, to form deflecting surfaces projecting across portions of the main conduit.
2. An inlet manifold for multi-cylinder engines comprising a main conduit having off-set portions and arcuate-shape branch conduits symmetrically merging into the main conduit, and having deflecting surfaces projecting across portions of the main conduit.
3. An inlet manifold for multi-cylinder engines, adapted to give substantially equal qualitative distribution of fuel to each cylinder, comprising a main conduit and branches communicating with the main conduit, the 25 division line between certain of the branches and the main conduit disposed in the stream of the main conduit to obstruct an area substantially proportional to the number of cylinders supplied each side of said division line, the main conduit being offset adjacent said division line so that the area of the conduit is not reduced.
4. An inlet manifold for multi-cylinder engines adapted to give substantially equal 35 qualitative distribution of fuel to the cylinders comprising a main conduit, a carburete branch connected to substantially the central portion of the main conduit, arcuate branch conduits communicating with the 40 main conduit and inclined toward the carburete branch connection, the division line between certain of the branches and the main conduit disposed in the stream of the main conduit to obstruct an area thereof 45 the main conduit being offset adjacent the main division line so that the area of the main conduit is not materially reduced.
5. An inlet manifold for multi-cylinder engines comprising a main conduit, arcuate branch conduits for various cylinders, a carburete branch connecting substantially 50 to the center of said main conduit, the shape of the main conduit and certain of the said branch conduits being such that a section 55 through the main conduit looking straight along inside of the conduit toward said branch will show a line of division across the area of said section the location of said line of division being such that when projecting on to the area of said section, it will divide the section in proportions according 60 to the number of impulses the engine will draw each side of said line of division, the two center branch conduits having their inlets coinciding substantially with the cir- 65
- 70 circumference of said main conduit, whereby substantially equal qualitative distribution of fuel is given to each cylinder.
6. An inlet manifold for multi-cylinder engines having six cylinders in a row to be supplied from one fuel source comprising a main conduit, six branch conduits, a vertical carburete branch connected to substantially the central portion of the main conduit, said main conduit having the central portion offset in a direction toward the outlet of the said branches a distance of approximately one-half the diameter of said main conduit, the length of said offset portion being sufficient to bring the line of division between the said main conduit and the branches for the second and fifth cylinders 75 substantially on the extended center line of said central portion of main conduit, said line of division being adapted to give equal 80 qualitative distribution between the first and second, and between the fifth and sixth cylinders, branches for third and fourth cylinders shaped such that the center line of the two branches forms an arc of a circle 85 tangent to the said main conduit, the line of division between the said branches being located on the surface of said main conduit without projecting into main conduit, said location of line of division being adapted 90 for equal qualitative distribution as between branch for third cylinder, and portion of the main conduit supplying first and second cylinders, and between branch for fourth cylinder and portion of main conduit 95 supplying fifth and sixth cylinders.
7. An inlet manifold for multi-cylinder engines embodying a plurality of cylinders in a row, to be supplied from one fuel source comprising a main conduit, a plurality of 100 branch conduits communicating therewith, a vertical carburete branch connected to substantially the central portion of the main conduit, said main conduit having its central portion offset in a direction toward the outlet from said branch conduits, a distance approximately equal to one half the diameter of said main conduit, the two central branch conduits communication with said central off-set portion of the main conduit.
8. An inlet manifold for multi-cylinder engines embodying a plurality of cylinders in a row, to be supplied from one fuel source comprising a main conduit, and a plurality 105 of branch conduits communicating therewith, the central portion of said main conduit being offset in a direction toward the outlet of said branches a distance of approximately one-half the diameter of the main conduit.
9. An inlet manifold for multi-cylinder engines embodying a plurality of cylinders arranged in a row and adapted to be supplied from one fuel source comprising a main conduit, a plurality of branch conduits 115
- 120
- 125
- 130

in communication with the main conduit, a carbureter conduit connected to substantially the central portion of said main conduit, said main conduit having its central portion off-set toward the outlet of the said branch conduits, and two intermediate branch conduits connected to said off-set central portion of the main conduit and having their outer walls constituting deflecting sur-

faces extending partially across the off-set 10 central portion of said main conduit.

In witness whereof I have hereunto set my hand this 24th day of November, 1917.

ARTHUR HOLMES.
